[57] CLAIM

The ornamental design for a telephone connector block, substantially as shown and described.

DESCRIPTION

FIG. 1 is a top plan view of a telephone connector block showing my new design;

FIG. 2 is a front elevational view thereof;

FIG. 3 is a side elevational view thereof as seen from the right hand portion of FIG. 2;

FIG. 4 is a rear elevational view thereof;

FIG. 5 is a side elevational view thereof, as seen from the left hand portion of FIG. 2;

FIG. 6 is a bottom plan view thereof;

FIG. 7 is a top perspective view thereof; and

FIG. 8 is a bottom perspective view thereof.

The terminal pins and associated structure are partially shown in FIGS. 2, 7 and 8 for convenience of illustration.

FIG. 2
